UNITED STATES PATENT OFFICE.

JOHN W. HYATT, OF NEWARK, NEW JERSEY.

EMBOSSING-TOOL.

SPECIFICATION forming part of Letters Patent No. 358,039, dated February 22, 1887.

Application filed January 12, 1886. Serial No. 188,352. (No model.)

To all whom it may concern:

Be it known that I, JOHN W. HYATT, a citizen of the United States, residing in Newark, Essex county, New Jersey, have invented certain new and useful Improvements in Embossing-Tools, fully described and represented in the following specification, and the accompanying drawings, forming a part of the same.

This invention relates to a tool for pressing sheet metal upon a matrix of any desired form; and it consists, essentially, in a bundle of rods clamped in a holder in such manner that the rods may move longitudinally upon one another.

15 My invention is particularly adapted for embossing or stamping sheet metal by longitudinal percussion with such a bundle of rods adapted to slide upon one another, and to thereby accommodate themselves to the surface of the matrix.

The invention is illustrated herein in two forms, Figure 1 showing the bundle of rods grasped in the hand of the operator and clamped together by an india-rubber elastic band near each end, and a matrix with a piece of sheet metal thereon being shown below the lower end of the bundle. Fig. 2 represents a mallet embodying my invention. Figs. 3 and 4 illustrate the bundle of rods connected with 25 a rotary crank to be reciprocated by steam-power, Fig. 3 being an end elevation at the front of the crank, and Fig. 4 an elevation at the side of the same. Fig. 5 represents in perspective the elastic clamp at the lower end 30 of the connecting-rod; and Fig. 6 is a section of the clamp in line $\alpha\alpha$ of Fig. 3, enlarged.

In Fig. 1, A is the matrix; B, the sheet metal; C, the bundle of rods, and D the elastic bands applied to the exterior of the bundle to hold 40 the rods together.

The sheet metal is represented as indented at B', with part of a design produced by pressing the sheet metal into a similar recess in the matrix. Such depression is effected by striking the sheet metal repeatedly with the ends of the rods, the metal yielding at each blow to the exact degree that each rod is able, separately, to overcome its resistance, and the rods sliding upon one another longitudinally to 45 reach the varying surface of the metal to

which it is applied. The process of shaping the metal is thus made very gradual, each blow forcing the metal into the matrix a little farther, and each rod ceasing to depress the metal when the latter is brought in contact 55 with the face of the matrix. If the depression in the matrix is deep, the metal would evidently be supported about its edges during the gradual depression of the included surface, the metal being stretched without injury, owing to 60 the limited force exerted by each rod separately, unless it be finally stretched beyond the limit of its endurance. If the metal be of a suitable nature, it may be annealed during the process, as in other stamping or embossing 65 processes; but the operation of the rods does not produce a hardness in such metal as copper with as much rapidity as in spinning sheet metal and analogous operations.

The rods may be varied in diameter to any 70 degree from one-hundredth to one-tenth of an inch or over, according to the thickness of the sheet metal, and I find that the effect of the separate rods upon the matrix is so slight that a wooden matrix may be used in the shaping 75 of thin sheet-copper, and a bed of type is not even injured by forming an embossed copy or stereotype of the same by laying a sheet of thin plater's metal over the face of the type, and hammering it with a bundle of fine rods. 80 This effect appears to result from the slight momentum carried by each of the rods, which, when no larger in diameter than a needle and not over one and a half or two inches in length, are too light to injuriously affect the surface 85 beneath the sheet metal, while their combined and repeated impact is sufficient to accomplish the desired effect.

In forming a bundle of rods to operate by hand, the rods may be made over a foot in 90 length and the bundle to weigh two or three pounds; but from what has been stated above it is obvious that the size of the rods and of the bundle may be indefinitely varied in proportion to the thickness of the sheet metal operated 95 upon, the force of the blows which are employed, and the depth of the desired indentations.

Fig. 2 represents a bundle of small rods clamped together by an elastic band of metal 100

having overlapping ends, (indicated at *a*.) and provided with a handle rigidly secured to the band and projected in such manner as to form with the rods a mallet to be used in place of the naked bundle shown in Fig. 1. Such metallic band is liable to slip toward one end or the other of the rods, unless lined with some adhesive substance, like india-rubber, which I have found is capable of adhering permanently to any desired part of the bundle. Such elastic bands have been shown without any metallic clamp at *D* in Fig. 1, but are shown in Fig. 6 at *D'* applied to the rods within a split clamp, *l*, shown at the lower end of the reciprocating connecting-rod *h*.

Figs. 3 and 4 show such connecting-rod pivoted by a universal joint, *e*, to a crank-pin, *e'*, mounted upon a counter-shaft, *f*, above an operating-table, *g*. A matrix, *H*, is represented upon the table, supporting a piece of metal, *I*, and the vibrating bundle is shown grasped by the hand of the operator to guide it in its application to the metal. The counter-shaft is provided with fast and loose pulleys *k*, to which a driving-belt could be applied and by which it can be stopped and started at pleasure. When in motion, the grasp of the metallic clamp *l* upon the bundle causes it to vibrate longitudinally up and down, and the labor of the operator is confined merely to directing it to different parts of the metal. The metal would in each case be preferably secured to the matrix by clamps or by pins, as at *m* in Fig. 1, and the matrix and metal could thus be readily moved around upon the table together to change its position from time to time beneath the tool.

In practice the table or matrix would be provided with means for adjusting the metal toward the tool, or the connecting-rod *h* would be formed with an elastic coupling at some part of its length to admit of its striking an elastic blow, so as to penetrate to different points in the surface of the matrix. The opposite parts of the split clamp embrace nearly the entire circumference of the bundle, and are pressed elastically toward the same by the yielding fingers *n*, by which the opposite parts of the clamp are attached, respectively, to the connecting-rod, the fingers being normally adjusted, so as to require opening to insert the bundle therein. The bundle would be previously provided with the india-rubber band *D'* at the point where the clamp is to be applied to form an adhesive bond between the rods and the clamp. The fingers *n* may be provided with means, as a screw, for pressing them toward one another to compensate for wear, or to clamp the bundle more firmly, if desired.

From the above illustrations it will be seen that my invention may be constructed in a variety of forms, and may be adapted to many uses which I have not mentioned herein. For instance, the rods themselves may be slightly crooked or bent near the ends to prevent the clamp from slipping off, and the bundle may be attached by suitable means to a vertically-reciprocating cross-head, as in various punching-machines, and the operator's attention devoted exclusively to moving the matrix and sheet metal beneath it.

I am aware that a bundle of wires has been rigidly bound together at one end with the free ends projecting like a brush and adapted to bend laterally to a slight degree when in use. Such a device may be used to stipple or ornament a metallic surface, but differs radically from my invention, in not operating by a direct longitudinal percussion against the sheet metal. By such latter method of operation, which I have invented, each rod in the bundle operates independently of the others, and must be held elastically, so that it may slide longitudinally in conformity with the depression to which it is applied. I therefore dis- claim a bundle of wires clamped together when operated by a lateral contact, which causes them to yield laterally instead of longitudinally, as in my invention.

The essential part of my invention is the holding of the bundle of rods in a clamp in such manner that they may move longitudinally upon one another when pressed upon the sheet metal, and I do not therefore limit myself to any particular means for retaining the rods in the bundle or striking them upon the metal, provided they operate by longitudinal percussion, but claim my invention in the following manner:

1. The embossing-tool consisting in a bundle of rods clamped together and separately movable longitudinally within the clamp and adapted to emboss sheet metal by longitudinal percussion, as and for the purpose set forth.

2. The combination, with a bundle of rods, of one or more clamps adapted to press them elastically together, so as to move longitudinally within the clamps, and mechanism for vibrating the bundle longitudinally to press the ends of the rods upon any opposed substance, as and for the purpose set forth.

In testimony whereof I have hereunto set my hand in the presence of two subscribing witnesses.

JOHN W. HYATT.
